UNITED STATES PATENT OFFICE

ROBERT MALCOM, OF CHICAGO, ILLINOIS

GOOGLES

Application filed November 25, 1929. Serial No. 409,468.

My invention relates more particularly to goggles involving eye-cups adapted to substantially inclose the eye cavities; the two eye cups being preferably loosely connected or linked together, while any suitable head-gearing or strap is employed for securing the goggle in place.

The invention has for its object the provision of eye cups composed of comparatively thin sheet opaque material, preferably sheet metal, adapted to removably hold the lenses securely in place, so that renewal of the lenses, when broken, or lenses of a different character, may be readily made by the user without need of special tools or devices.

The objects and advantages of my invention will be readily comprehended from the following detailed description of the accompanying drawing, wherein:

20 Figure 1 is a face view of one of the eye-cups, with only a portion of the eye-cup connecting chain and a portion of the attaching strap being shown.

25 Figure 2 is a horizontal cross section taken substantially on the line 2—2 of Figure 1.

Figure 3 is a vertical sectional view taken substantially on the line 3—3 of Figure 1, viewed in the direction of the arrows.

30 Figure 4 is a view similar to Figure 3, showing the eye-cup in opened or spread condition.

Figure 5 is an end elevation of an eye-cup as viewed from the left in Figure 1.

35 Figure 6 is a similar view, illustrating the eye-cup in open or spread condition.

Figure 7 is a detail sectional view, taken substantially on the line 7—7 of Figure 5, as viewed by the arrows.

40 My improved goggle, which is intended to prevent dirt and particles of material from entering the eyes, as well as to exclude objectionable side light, comprises a pair of eye-cups which are identical in construction so that description of one eye-cup will suffice.

45 The eye-cups are each made of sheet metal cut to proper size and shape so as to permit being folded into substantially circular form, as shown in Figure 1.

50 The blanks are cut to fit about an eye-socket, having a short side wall 10, adapted

to fit the eye-socket adjacent to the nose, and provided with some suitable connecting member or nose bridging element, preferably in the form of a loose or yielding chain, of which a portion is shown at 11, for yielding 55 ly connecting the two eye-cups of the goggle.

The blank is cut to somewhat meet the curvature of the face adjacent to the eye and to provide the wide side wall 12 which is 60 disposed adjacent the temple of the wearer.

The blank is folded to provide a split cup with the opposite edges of the blank, normally brought into abutting relation, as shown at 13 in Figure 3.

65 In cutting the blank complementary portions are produced at the ends; that is one end is provided with a slot 14, see Figure 4, while the other end is provided with a correspondingly shaped tongue 15 which normally fits into and fills the slot 14, as shown in Figure 3.

70 The outer marginal edge is formed to provide a groove 16 to receive the perimeter of the lens 17; the diameter of the groove when the cup is in normal condition being such that the lens will be firmly held in place.

75 In order to hold the abutting edges 13 in proper relation and therefore maintain the split eye-cup in normal lens clamping condition, I provide a holding and controlling element which is shown in the nature of a combined locking and head-strap attaching plate 18.

80 The member 18, of sheet metal, is of suitable width to lap or extend beyond the abutting ends 13 of the encircling band or cup and is disposed transversely of the band or cup as shown in Figure 5.

85 The member 18 is shown provided with a number of diagonally arranged or sloping slots 19, all preferably of the same length or configuration shown more clearly in Figure 5. These slots are arranged in pairs on opposite sides of the longitudinal axis of the member 18 as shown. Each end 13 of the eye-cup wall is provided with a pair of small outward projections preferably in the form of small eyelets 20 which are inserted through wall 12 and through the slots 19 of the con- 90 95 100

trolling member 18; the outer outwardly upset or turned ends of the eyelets being of larger diameter than the width of the slots 19, so that the plate or controlling member 18 will be properly held in place.

5 The slots 19 slope downwardly and outwardly from the upper ends which are disposed toward the lens-holding perimeter of the cup. With the slots 19 slightly wider than the 10 diameter of the intermediate body portion of the eyelets, it is apparent that the controlling element or member 18 may be moved transversely of the eye-cup wall so as to present opposite ends of the slots 19 to the eye- 15 lets 20. As the slots slope toward the opposite sides of the member 18 and therefore farther away from the plane of the meeting edges 13 of the eye-cup wall, it is apparent that movement of the member 18 transversely 20 of the eye-cup will induce the meeting edges 13 of the cup to be spread apart or brought together depending upon the direction of movement of member 18.

That is to say, with the member 18 positioned as shown in Figure 5 where the eyelets are located at what may be termed the 25 upper ends of the slots 19, the eye cup will be completely contracted in closed lens-holding condition, as shown in Figure 3. Upon 30 shifting or moving the member 18 transversely of the cup in a direction toward the lens-holding rim, the eyelets will ride lengthwise of the slots 19 toward the outwardly disposed ends 19a. It is apparent that the meeting 35 ends 13 of the cup wall will be spread apart in the manner disclosed in Figures 4 and 6. In this spread apart or opened out condition, the lens 17 will be released, as shown in Figure 4, thus permitting easy insertion 40 or replacement of the lens, which may then be clamped in place by simply moving member 18 in the opposite direction so as to position the eyelets in the slots, as shown in Figure 5.

45 The tongue 15 and slot 14 are preferably of such length that the tongue will partially extend into the slot when the cup wall is in its fullest distended or opened out condition, as shown in Figure 4, so as to ensure proper 50 alignment of the abutting ends 13 being maintained.

The lower end of plate or member 18, namely the end disposed away from the lens holding rim of the cup, is shown bent slightly 55 outward at 21, Figure 2; and this outwardly bent end, which is of comparative width, is transversely slotted for attaching the end of the head-gear or strap thereto; a portion of the strap being shown at 22.

60 With the head-strap secured to the end 21 of member 18 it is apparent that pulling strains on the strap will be exerted in proper direction on member 18 to maintain the eyelets at the upper converging ends of the slots 65 so that the lens will be firmly clamped in

place. The upper end of member 18 is bent slightly outward so as to ride over the lens-holding rim 16 of the eye cup.

By curving the diverged ends of the slots toward one side of the longitudinal axes of 70 the slots, a complete spread of the eye-cup walls is induced while at the same time accidental movement of the member 18 through the contracting force of the eye-cup walls will be prevented until the member 18 is 75 manually shifted in the right direction. The member 18, as shown, provides head-gear attaching means and means whereby positive movement of the eye-cup walls is induced.

I have shown the member 18 provided with 80 a number of slots on each side of the longitudinal center of the member and the walls of the eye-cup provided with an equal number of eyelets, but it is apparent that the number of slots and eyelets may be changed and that 85 the slot-engaging elements need not be in the nature of the eyelets shown; such changes being possible without, however, departing from the spirit of my invention.

90 What I claim is:—

1. In a goggle, an eye-cup having a side wall of sheet material formed to bring the ends of the sheet into adjacent relation, while one of the edges of the sheet is formed to provide a lens-holding groove; a plate disposed 95 transversely of the eye-cup in lapping relation with the adjacent ends of the cup-wall, said plate being provided with diverging slots; and protruding portions on the cup-wall disposed through said slots whereby the 100 position of said plate controls the relation of the adjacent ends of the cup-wall.

2. In a goggle, an eye-cup formed of sheet material bowed into a lens-holding frame, the juxtaposed ends having matching portions 105 to maintain alignment of said ends; the frame adjacent to said ends having protruding portions; and frame clamping means slidably transversely of the frame and provided with diverging slots adapted to receive 110 said portions, whereby movement of said means in one direction causes the frame ends to spread apart while movement of said means in the opposite direction causes said frame ends to move into juxtaposition. 115

3. In a goggle, eye-cups formed of sheet material bowed into lens-holding frames with the ends of the sheet in juxtaposition; said ends having a matching tongue and slot 120 for maintaining proper alignment of said ends; said frame adjacent to the ends being provided with protruding eyelets; and a slotted member adapted to have the eyelets extend through said slots, said slots diverging toward opposite sides of the member so 125 that movement of the member in one direction causes the frame ends to move toward each other while movement of the member in the opposite direction causes the frame ends to move away from each other. 130

4. In a goggle, an eye-cup formed of sheet material formed into a lens-encircling frame, the frame adjacent to its ends being provided with outwardly protruding elements; and a divergently slotted plate slidably held in place by said elements extending through the slots, whereby movement of said plate causes said frame to expand or to contract, said plate having an outwardly disposed slotted end for attachment of a head encircling strap.
5. In a goggle, an eye-cup formed of sheet material bowed into a lens-encircling frame adapted to fit about the eyes of the wearer, the juxtaposed ends of the frame-sheet being provided with correlated portions for maintaining alignment of said ends; a plate disposed transversely of the juxtaposed ends of the frame so as to lap the joint, said plate being adapted to slide in directions toward and away from the lens-holding edge of the frame, with its end adjacent to the face-engaging end of the frame provided with a head strap fastening portion; and means associated with said plate and the frame whereby a movement of the plate causes the frame to expand or contract for releasing or clamping a lens in the frame.
6. In a goggle, an eye-cup made of resilient material formed into cylindrical shape with the ends in opposing relation; a member arranged to lap the ends of the cup wall; and slot and pin connections between both ends of the cup-wall and the member adapted to permit the member to bodily slide transversely of the eye-cup, the slots of said connections being so formed that sliding the member in one direction induces a spreading of the ends while sliding the member in the opposite direction causes said ends to be brought toward each other.

ROBERT MALCOM.
